UNITED STATES PATENT OFFICE.

AMARIAH W. JACKSON, OF CHICAGO, ILLINOIS.

STEAM TURBINE-ENGINE.

No. 840,771.

Specification of Letters Patent.

Patented Jan. 8, 1907.

Application filed May 12, 1906. Serial No. 316,547.

To all whom it may concern:

Be it known that I, AMARIAH W. JACKSON, a citizen of the United States, residing at 315 East Sixty-third street, in the city of Chicago, county of Cook, and State of Illinois, have invented a new and useful Improvement in Steam Turbine-Engines, of which the following is a specification.

My invention relates to that class of engines known as "steam-turbines."

The object of my invention is to produce a simple and cheaply-constructed engine in which by the fullest application of the principle of deflection to secure the largest percentage of the initial and expansive force of the steam entering the engine and convert it into motion; that while constructed of but two parts will be automatic in action.

The manner in which I accomplish my object is set forth in the following specification and illustrated in the accompanying drawings, in which—

Figure 1 is a central vertical section on the line 1 1, Fig. 9. Fig. 2 is a central vertical section on line 1 1, Fig. 9, showing the construction of the main supporting fixed half of the engine. Fig. 3 is a vertical sectional view on the line 1 1, Fig. 9, showing the construction of the supported rotatable part of the engine. Fig. 4 is a vertical central cross-sectional view on the line 6 6, Fig. 8, showing the construction of the main supporting fixed half of engine. Fig. 5 is a vertical central cross-sectional view on the line 6 6, Fig. 8, showing the construction of the supported rotatable half of the engine. Fig. 6 is a central vertical cross-sectional view on the line 6 6, Fig. 8, showing both halves of the engine in the operating position. Fig. 7 is a detail sectional view of one of the steam-ports, showing the corrugated faces therein. Fig. 8 is a side view of the engine, and Fig. 9 is a front view of the engine.

In the drawings, A indicates the main stationary half of the engine, cylindrical in form, provided with a base A'. One side A² of this forms an integral part of this half and has a central aperture A³, into which a steam-supply pipe A⁴ is attached. This aperture opens into a steam-chamber A⁵. Extending through the wall of this chamber is a series of steam-ports B. The direction of these ports is tangential to the axis of the chamber and engine. The external face A⁶ of the wall of this steam-chamber forms a central finished circular tapered bearing A⁷.

Concentric with this bearing and spaced therefrom is a second cylindrical taper bearing A⁸, forming an integral part of the part A. Extending through this bearing is a series of steam-ports B', corresponding in number with ports B in the bearing A⁷. These ports in cross-section are V-shaped, the apex of the angle of each port being on an imaginary concentric circle through the longitudinal center of the bearing A⁸.

The tangential direction of the inner half B² of the ports B' in the bearing A⁸ is opposite to the tangential direction of the ports B in the bearing A⁷, the tangential direction of the outer half B³ of the ports B² being the same as that of the ports B. Spaced from the bearing A⁸ is the outer cylindrical part A⁹ of the stationary half A. The interior periphery A¹⁰ of this part is finished to a taper bearing-surface. Extending through this cylindrical part is a series of steam-ports B⁴, the same in number, shape, and direction as the ports in the bearing A⁸. These ports open into an exhaust-chamber B⁵, which encircles this series of ports and permits the steam therefrom to escape through an exhaust-pipe B⁶. At the bottom of the V-shaped spaces C are annular channels C'.

The rotatable half D of the engine is adapted to fit the concentric bearings in the stationary half A. The central part forms a taper cylinder D', adapted to fit on the bearing A⁷. The wall D² of this cylinder is tapered externally to fit the inside face of the bearing A⁸. Extending through this wall is a series of steam-ports E, corresponding in number with the ports B in the bearing A⁷. In cross-section these ports are V-shaped, the apex E' of the angle being on an imaginary concentric circle through the longitudinal center of the wall D² of the cylinder D'. The direction of the inner half E² of each of these ports is in the same tangential direction as that of the ports B in the bearing A⁷, the outer half E³ of each port extending at an angle thereto in the opposite direction. The inner openings E² of these ports correspond in size and register with the ports B in the bearing A⁷, and the outer openings E³ register with the inner openings B' of the bearing A⁸. Spaced from and concentric with the wall D² of the cylinder D' and forming an integral part of the half D is a cylindrical ring D³. This ring is tapered and adapted to fit in the annular space C formed by the bearing A⁸ and bearing-surface A¹⁰ of

the outer cylindrical part A⁹ of the main part A. Extending through this ring is a series of ports E⁴, corresponding in number with and in the same angular shape and direction as ports E in the part D². These ports are adapted to register with the ports B' and B³ in the bearings A⁸ and A⁹. At the bottom of the spaces F are channels F'. The channels C' and F' at the bottom of the spaces C and F are adapted to allow a clearance for the ends of the bearing-surfaces, and thereby prevent the wearing of shoulders therein.

When the two halves of the engine are constructed and finished as described and shown and the part D is placed into the part A and adjusted therein by any suitable means adapted to hold the parts in adjustment, the operation of the engine is as follows: A steam-supply is turned into the chamber A⁵ through the supply-pipe A⁴. The steam passes from this chamber through the ports B and is deflected so that it strikes the inner half E² of the ports E in the rotatable part D of the engine and is again deflected by the outer half E³ of the ports E and then enters the ports B' in the part A. The action of the steam against the angular faces of the ports E forces the part D to rotate in the direction of the arrows. The steam is deflected again in the ports B' in the direction of the rotation of the part D. The steam then enters the ports E⁴ in the part D, impelling the part D in its rotary motion, and escapes through the ports B⁴ into the exhaust-chambers B⁵, from whence it passes out of the engine through the exhaust-pipe B⁶. The rotary movement of the part D can be transmitted from the shaft G or by other means affixed or attached to any part of the outer surface of the part D.

It is obvious that when the steam is turned into the engine if the ports E in the cylindrical part D² do not register with the ports B of the steam-chamber A⁵ a slight rotary movement of the part D will bring the ports into line and the engine will rotate at once. It is also apparent that the number of concentric cylindrical bearing-surfaces and series of ports in the fixed and rotatable parts of the engine can be increased with the size of the engine and the engine be thereby adapted to utilize the full expansive force of the steam as it passes through the ports from the center to the circumference. For the purpose of retarding the passage of the steam through the ports of the rotating part of the engine and to thereby increase its propelling force I construct the forward wall of each of said ports with corrugations H, as shown in the fractional detail sectional view in Fig. 7. It is also obvious that the stationary body may be made of a back plate and supporting-base and that the steam-chamber and concentric cylindrical bearings can be finished in separate parts and attached to said back

plate, and so with the rotatable part. The main body forming the back of that part can be prepared and finished and the concentric cylinders attached thereto.

The engine can also be adapted so that the number of ports may vary in both the stationary and rotatable parts and the steam be admitted through the periphery of the engine and exhaust throughout its central part, and any fluid under pressure can be used as the propelling or impelling force.

What I claim, and desire to secure by Letters Patent, is—

1. A turbine-engine formed of two members, one of said members being stationary and adapted to stand or be affixed in a permanent position, said member having a central inlet for admission of steam, a steam-chamber forming an extension of said inlet, the walls of said chamber forming an external central cylindrical taper bearing, a series of tangential steam-ports extending through the taper wall of said chamber and bearing; a taper cylindrical external and internal bearing concentric with said central bearing and spaced therefrom; a series of tangential V-shaped steam-ports extending through said bearing; an internal taper cylindrical bearing, concentric with said external and internal bearing and spaced therefrom; a series of V-shaped tangential steam-ports extending through said bearing; an exhaust-chamber encircling said ports in said internal bearing, said ports opening into said exhaust-chamber, said exhaust-chamber having an outlet through the exterior wall of said member; a rotatable member of said engine, said member having a central external and internal cylindrical taper bearing adapted to fit the corresponding central external bearings in said stationary member, a series of V-shaped tangential steam-ports extending through the wall of said cylinder, said ports corresponding in number and adapted to register with the ports in said corresponding external central bearing in said stationary member; a taper cylindrical external and internal bearing concentric with said central external and internal bearing and spaced therefrom, said bearing being adapted to fit the corresponding internal and external bearings in the stationary member, a series of V-shaped steam-ports, corresponding in number and adapted to register with the ports in said bearings in said stationary part, and means for holding and adjusting said rotatable member in the stationary member substantially as and for the purposes specified.

2. In a turbine-engine of the kind described, the combination of a stationary member, having a central steam inlet and chamber, the external wall of said chamber forming a central external cylindrical bearing, pierced with a series of tangential steam-

ports, and concentric internal and external cylindrical bearing spaced from said central bearing pierced with a series of V-shaped tangential steam-ports, and an internal concentric bearing spaced from said external and internal concentric bearing, pierced with a series of V-shaped tangential ports, and an exhaust-steam chamber encircling said internal concentric bearing and connected with and forming an exhaust-outlet for the said steam-ports; with a rotatable member having taper concentric cylindrical bearings, corresponding with and adapted to fit the bearings in said stationary member, said bearings in said rotatable member being pierced with V-shaped tangential steam-ports, corresponding in number and adapted to register with the steam-ports in the bearings in said stationary parts; and means for adjusting and holding said rotatable member in said stationary member.

3. In a turbine-engine of the kind described, the combination of a stationary member having an external axial taper bearing; an axial steam-inlet and chamber within said bearing; radial tangential ports extending from said chamber through said bearing; a plurality of taper cylindrical bearings concentric with said axial bearing and spaced 30 therefrom and from each other; radial tangential ports extending through each of said bearings; an exhaust chamber and outlet, said chamber being concentric with said cylindrical bearings; radial tangential ports extending through the outer cylindrical bearing into said exhaust-chamber, with a rotatable member having an internal axial bearing adapted to fit said axial bearing on said stationary member; a plurality of taper cylindrical bearings adapted to fit and to be rotatable on said cylindrical bearings on said stationary member; radial tangential ports extending through said axial and said cylindrical bearings adapted to register with said 45 ports in said stationary member.

4. In a turbine-engine of the kind described, the combination comprising a supporting member, having a base and central aperture for a steam-inlet; a cylindrical steam-chamber affixed to said supporting member, said chamber being pierced with a series of tangential steam-ports, and finished externally as a central cylindrical bearing; a cylindrical ring affixed to said supporting member concentric with said central bearing, said ring being pierced with a series of tangential V-shaped steam-ports; a cylindrical ring affixed on said supporting member, concentric with the inner ring and central bearing, said ring being finished internally and pierced with a series of tangential V-shaped steam-ports, said ports opening

into an exhaust-chamber forming the body of said ring and having a steam-outlet; a rotatable member, consisting of a supporting plate, a central cylindrical ring attached to said plate, said ring being pierced with a series of tangential V-shaped steam-ports; a cylindrical ring attached to said plate concentric to and spaced from said central ring, 65 said ring being pierced with a series of tangential V-shaped steam-ports, said cylindrical rings attached to said plate, being adapted to fit into the cylindrical rings, and bearings attached to said supporting member, and adapted to be rotated in and on said bearings; said steam-ports in said rings being adapted to register with each other and to permit the passage of steam therethrough, and means for adjusting and holding said 80 members and their bearing parts together.

5. In a turbine-engine of the kind described, the combination of one stationary member with one movable member, said stationary member having an external axial bearing; a central steam-inlet in said bearing; radial tangential ports from said inlet through said bearing; cylindrical bearings concentric with said axial bearing, spaced therefrom and from each other; radial tangential ports extending through said bearings, and an exhaust-port concentric with said bearings, radial ports connecting said exhaust-port with said bearings; said movable member having an internal axial bearing and cylindrical concentric bearings adapted to fit said bearings on said stationary member and to be revolved thereon; radial tangential ports extending through said axial and cylindrical bearings adapted to register 100 with said ports in said stationary member.

6. In a steam-engine of the kind described, the combination of a stationary part consisting of series of concentric cylindrical bearings, pierced by a series of tangential steam-ports, the advance face of each of said ports being corrugated across the line of passage of the steam, and a rotative part consisting of a series of concentric cylindrical bearings pierced by a series of tangential steam-ports, 110 said ports having corrugated faces, said corrugations being across the line of the passage of the steam, the cylindrical parts of said stationary and said rotatable parts of said engine being adapted to fit each other and the 115 steam-ports to register and permit the passage of steam from the center of said stationary part through all of said stationary and rotative cylinders.

AMARIAH W. JACKSON.
